UNITED STATES PATENT OFFICE.

CHARLES HIERL, OF CLEVELAND, OHIO.

BUFFER FOR CARS.

Application filed December 22, 1921. Serial No. 524,269.

To all whom it may concern:

Be it known that I, CHARLES HIERL, a citizen of the United States, residing at Cleveland, in the county of Cuyahoga and 5 State of Ohio, have invented certain new and useful Improvements in Buffers for Cars, of which the following is a specification.

This invention relates to buffers for cars, 10 and has for its main object to provide a buffer which is adapted to slide upon the rails of a track for reducing the jar in bringing a car to a standstill.

Another object of the invention is to provide 15 a buffer of simple and practical construction, which will support the rear wheels of a car for utilizing the weight to increase the braking power of the buffer.

A further object of the invention is to provide 20 a buffer of said character, which will be drawn back to its original position by the car when the car is moved away after being brought to a standstill.

With the above and other objects in view, 25 as will be readily understood, the invention will be hereinafter fully described as illustrated in the accompanying drawings, and the novel features thereof will be distinctly pointed out in the appended claims.

Similar characters of reference are used 30 in the several drawings to designate corresponding parts.

Figure 1 is a side elevation of a track with a car thereon, and a buffer constructed 35 in accordance with my invention in position upon said track for bringing the car to a standstill,

Fig. 2 is a plan view of the buffer upon the track as illustrated in Fig. 1,

Fig. 3 is an end view of Fig. 2,

Fig. 4 is a side elevation of the buffer,

Fig. 5 is a similar view to Fig. 4, one side of the buffer being eliminated, and the pull-bar engaging the axle of a car for drawing the buffer back to its original position after the car has been brought to a standstill, and

Fig. 6 is a front view of Fig. 5.

Referring to the drawings, 1 represents 50 rails fixed to cross ties 2, and 3 a car carried by axles 4, which are supported by wheels 5 for travelling upon said rails, all of ordinary construction. The buffer consists of a pair of shoes 6 and 7, which are adapted 55 to slide longitudinally upon the rails of the track and support longitudinally extending

sides 8 and 9 connected by a transverse block 10. The shoes 6 and 7 extend forwardly of the sides 8 and 9 for accommodating the wheels 5 of the car 3, and said sides extend beyond face 11 of the block 10 and their edges are curved inwardly at 12 to correspond with the peripheries of said wheels. Depending flanges 13 and 14 at the outer sides of the shoes 6 and 7 are adapted to engage the outer sides of the rails of the track to retain the buffer thereon. When a car is backed so that a pair of its wheels rest upon the forwardly extending portions of the shoes 6 and 7 and said wheels engage 60 the curved edges 12 of the sides 8 and 9, the buffer is forced or pushed along the rails of the track and the weight of the car also tends to increase the friction between the shoes and the rails, thus bringing the car 65 to a standstill and avoiding any sudden jarring of the car as is the case when striking a fixed or stationary buffer.

In order to return the buffer to its original position when the car is drawn away after 70 being brought to a standstill, a pull-bar 15 is pivoted at 16 between a pair of lugs 17 and 18 projecting from the face 11 of the transverse block 10, and its free end is provided with a suitable hook 19, which is adapted 75 to engage the axle 4 of the car as the car is drawn away. For disengaging the hook 19 of the pull-bar 15 from the axle 4 of the car when the buffer is again at its original 80 position, a guide member 20 is fixed to one of the cross ties 2 at such position as to be engaged by said pull-bar, and this causes the hook of the pull-bar to be lifted clear of the car axle, thus releasing the car and leaving the buffer in its original position for 85 the bringing of the next car to a standstill. The under edge of the pull-bar 15 is preferably swelled out at 21 to provide a cam for engaging the guide member 20. The buffer may be set with the pull-bar 15 resting upon 90 the guide member 20, or it may be left at some other place along the track, in which case it is necessary that the free or hook end of the pull-bar should not be below the car 95 axle. For holding the pull-bar so that its hook end will be above the car axle, the pivoted end of the pull-bar is provided with a depending lip 22 for engaging the face 11 of the transversal block 10, and in order 100 that the hook end of the pull-bar will slide over the car axle, its lower edge is beveled at 23,

From the description and accompanying drawings, it is readily seen that such a buffer will bring a car to a standstill without sudden jarring of the same, that the buffer is of simple and practical construction, that it will be drawn by the car or returned by the car to its original position as the car is drawn away, and that it may be left at any position upon a track or used on different tracks for bringing a car to a standstill. It will be understood that slight changes in the details of construction may be made within the scope of the claims.

Having fully described my invention, 15 what I claim is:

1. In a buffer, the combination of means adapted to slide upon a track for bringing a moving body to a standstill, a pull-bar, the pull-bar having one end pivoted to said means, and the other end of the pull-bar being adapted to be engaged by the body when the body is moving in one direction to actuate said end of the pull-bar upwardly and to effect connection with the body when 25 the body moves in the other direction, substantially as described.
2. In a buffer, the combination with a car having an axle, of means adapted to slide upon a track for bringing the car to a standstill, a pull-bar, the pull-bar having its rear end pivoted to said means, a hook at the forward end of the pull-bar adapted to engage the car axle, the hook having a bevelled edge adapted to be engaged by the 35 car axle when the car moves rearwardly to cause the hook to pass over the car axle, and the hook being adapted to be connected with the car axle when the car moves forwardly, substantially as described.
3. In a buffer, the combination of a block adapted to slide upon a track for bringing a car to a standstill, a pull-bar pivoted to the block, and the pull-bar being provided with means for effecting a connection with a car when the car is withdrawn from the block, substantially as described.
4. In a buffer, the combination of a block adapted to slide upon a track for bringing a car to a standstill, a pull-bar pivoted to the

block, the pull-bar being provided with 50 means for effecting a connection with a car when the car is withdrawn from the block, and means for causing the disconnecting of the pull-bar from the car as it moves, substantially as described.

5. In a buffer, the combination of a block adapted to slide upon a track for bringing a car to a standstill, a pull-bar pivoted to the block, the pull-bar being provided with 60 means for effecting a connection with a car when the car is withdrawn from the block, and a guide member for causing the disconnecting of the pull-bar from the car as it moves, substantially as described.

6. In a buffer, the combination of a block 65 adapted to slide upon a track for bringing a car to a standstill, a pull-bar pivoted to the block, the pull-bar having a hook at its free end for effecting a connection with a car when the car is withdrawn from the 70 block, and the pull-bar having means at its pivoted end for engaging said block to hold its free or hook end at a certain height, substantially as described.

7. In a buffer, the combination of shoes 75 adapted to slide upon rails, sides supported by the shoes, a block connecting the sides, the shoes extending forwardly of said sides for accommodating the wheels of a car, the sides having curved edges for receiving the 80 wheels of the car, and means for effecting the connection of the block to the car when the car is moved off said shoes, substantially as described.

8. In a buffer, the combination of shoes 85 adapted to slide upon rails, sides supported by the shoes, a block connecting the sides, the shoes extending forwardly of said sides for accommodating the wheels of a car, the sides having curved edges for receiving the 90 wheels of the car, a pull-bar pivoted to said block, and the pull-bar having a hook at its free end for effecting a connection with the car when the car is withdrawn from the block, substantially as described.

In testimony whereof I affix my signature.

CHARLES HIERL.
